UNITED STATES PATENT OFFICE.

THOMAS J. KELLEHER, OF CHICAGO, ILLINOIS.

BENDING MACHINE.

Application filed June 29, 1927. Serial No. 202,843.

This machine relates to a machine adapted to bend sheet metal plates and strips of ductile material, for architectural and other purposes.

5 Among the objects of this invention is to obtain a machine by means of which sheet metal of considerable thickness and length can be bent, without said machine being of any considerable weight, and without the 10 meeting edges of the dies of the machine being forced to bend out of horizontal planes. An additional object is to obtain a bending machine which is economically made, is durable, not liable to be broken, or 15 to get out of order, and one the operation whereof is readily understood by those familiar with the art of bending sheet metal. An additional object is to obtain a bending machine which will be economical of the 20 power required to operate it.

In the drawings referred to Fig. 1 is a front elevation of a construction embodying my invention.

Fig. 2 is an elevation of one end of the 25 construction illustrated in Fig. 1.

Fig. 3 is a rear elevation of said construction.

Fig. 4 is a vertical section of said machine, 30 taken on line 4—4 of Fig. 1, viewed as indicated by arrows.

Fig. 5 is an enlarged vertical section taken on line 5—5 of Fig. 1, viewed as indicated by arrows.

Fig. 6 is a perspective of a link member, 35 duplicates whereof form a series of toggle joints which are the driving members of the upper and movable die of the machine.

Figs. 7 and 8, respectively, are perspectives of link members of an additional 40 toggle joint which is the driving element of the series of toggle joints of the machine.

A reference character applied to designate a given part indicates said part throughout the several figures of the drawings, wherever the same appears.

1 represents I-beams, which are arranged to form the base of the machine. 2 represents metal plates which are mounted on horizontal plate 3, which is interposed between said metal plates and the I-beams 1. Metal plates 2 are in vertical parallel planes. 4 represent bolts and 5 a plate which is rigidly secured to parallel plates 2 by said bolts. The vertical plate 5 is also, preferably secured to the forward edge of plates

2 by welding, as at 6, Fig. 2, in the ordinary manner. 7 represents bolts by means of which the motor X, (which forms no part of the invention), is secured on table 8, 9 represent diagonally extending bars which, 60 at their lower ends, are secured to adjacent plates 2 by bolts 10, and to table 8, at their upper ends, by bolts 11. 12 represents a bar which is secured, at its lower end, by angle iron 13 and bolts 14, to plate 3. Bar 65 12 is also secured in position by bars 12^a, Figs. 2 and 3, and bolts 12^b and 13. 15 represents a journal bearing which is mounted on the upper end of bar 12, as by bolts 16, Fig. 3. 17, Figs. 1, 2 and 5, represents 70 a bed, on which the lower die, 18, is mounted, being secured thereto, as by the bars 19 and bolts 20. 21, Fig. 2, represents the base of bed 17, and is mounted on the several vertical plates 2; said plates being cut away 75 to obtain the horizontal tables 22. 23 represents the upper and movable die, which is mounted on the lower edge of the horizontally disposed bar 24. 25 represent the members of a plurality of toggle joints forming 80 a series, which are, respectively, pivotally joined by pins 32. The lower members of each series of toggle joints are joined at their lower ends, by pivots 26 to said horizontal bar 24. The bar 24 is cut away, ad- 85 jacent to the lower ends of said lower members 25, as at 27, Fig. 1, to permit said members to be pivotally moved on pins 26 into the position in which they are illustrated in Fig. 1, or into substantially said position. 90 28 represents a member or tongue at one end of member 25, and 29 a recess at the other end of said member, (see Fig. 6). 30 represent apertures at one end of member 25, and 31 a similar aperture at the other end of said member. Said recess 29, in one end of member 25, permits the tongue 28 of an additional member 25, which is to be linked thereto, to be inserted therein, and a pin, 32, to be inserted in apertures 30, 31, 95 to pivotally join said members. The recess 29 in the lower end of the lower one of the pivotally joined members 25, permits the upper edge, 31, of bar 24, to be inserted therein, and said lower one of said members 100 25 and said bar 24 to be pivotally connected together by pins 26, which extend through a corresponding aperture in upper edge 31 of bar 24. 33 represent horizontally disposed bars, which are provided with aper- 110

tures whereby said bars are mounted on pivots 32, and secured thereon as by cotter pins 34. One of said bars 33 join the several toggle joints on the left hand side of the machine as viewed in Fig. 1, and the other one of said bars 33 join the toggle joints on the right hand side of the machine. 35, 36, Figs. 1, 7 and 8, represent the members of an additional toggle joint, which pivotally 10 join adjacent ends of bars 33. The bars 33 extend towards each other beyond the members 25 which form the two series of toggle joints. The lower ends of members 35, 36, are respectively provided with apertures 37, 15 and in assembling said members 35, 36, the apertures 37 respectively are made to register with corresponding apertures adjacent to the ends of bars 33, so that pins 38 may extend through said apertures in bars 33 and 20 members 35, 36, to pivotally join said members to said bars. The upper end of member 35 is provided with recess 39 and aperture 40, and the upper end of member 36 is provided with tongue 41 and aperture 42. 25 When members 35, 36, are assembled, the tongue 41 or member 36 is placed in recess 39, or member 35, and apertures 40, 42 are made to register, so that pin 43, Figs. 1 and 4, may extend through 44, Figs. 1, 2 and 4, 30 represent horizontal bars which extend the length of the machine, the front one of said bars being bent, as indicated by character 45, in Figs. 1 and 2, to position the part 46 of said front bar 44, in front of the members 35 and 36 of the toggle joint which joins adjacent ends of bars 33. Bars 44 are mounted on pins or bolts 47, which form the fulcrums of the upper ends of the upper members 25 of the two series of toggle joints. 35 40 48 represent vertical members, which are provided with recesses at their lower ends into which tongues 28 of the upper ends of the upper members 25 of the two series of toggle joints extend, and with apertures 45 through which the several pins or bolts 47, extend.

The upper ends of members 48 are provided with longitudinally extending holes which are, respectively, provided with internal screw threads, and 49 represent external screw threads corresponding with and fitting into said internal screw threads. Screw threads 49 are on the lower ends of vertical members which are rotatably mounted in plates 2, adjacent to the forward edges thereof, and 50 represent worm gears, (Figs. 1 and 2), which are rigidly secured on the upper ends of said vertical members, to turn therewith. 51 represent spirals or worms which intermesh with the teeth of worm gears 50. Worms 51 are rigidly secured on shaft 52, and said shaft is rotatively mounted in brackets 53.

The bars 44 and the upper ends of the members 25 of the two series of toggle

joints, are adjusted vertically by means of members 48, screw threads 49, wheel 50, shaft 52 and worms 51 thereon, to correspond with the thickness of the sheets of metal which are designed to be bent between bed die 18 and movable die 23.

54 represents a rotative shaft which is mounted in journal bearings 15, 55. 56 represents a hub which is provided with a groove, and 57 represents a disk which is, 75 preferably, integral with hub 56, and which necessarily is secured to said hub to turn therewith. The shaft 54 is provided with a key way, 58. 59 represents a handle which is fulcrumed on pin 60, and 61 represent pins which are rigidly secured in the upper forked end of handle 59, to extend into the groove in hub 56, to control the sliding position of said hub and of disk 57 on shaft 54. 62 represents the movable member of a 80 friction clutch and 63 spring members interposed between disk 57 and movable member 62 of the friction clutch. Hub 56, disk 57 and movable member 62 are keyed to shaft 54, to turn therewith, and are slid- 90 able on said shaft. 64 represents a clutch member which is loosely mounted on shaft 54, and 65 represents a pulley which is provided with a heavy rim, to act as a balance wheel, which is also loosely mounted on 95 shaft 54, and is rigidly secured to clutch member 64. 66 represents a driving belt which extends over the driving pulley 66^a on the shaft of motor X, and over the wheel 65, thereby driving said wheel 65 and clutch member 64, when said motor X is energized. To cause shaft 54 to rotate the movable clutch member 62 is, by means of handle 59, hub 56, disk 57, and interposed spring members 63, moved along the shaft 100 54 into frictional engagement with clutch member 64.

67, 68, respectively represent shafts which are rotatably mounted in suitable journal bearings mounted on the plates 2. The several shafts 54, 67 and 68, are connected by reducing gears, which comprise the pinion 69, rigidly mounted on shaft 54, the gear wheel 70 mounted on shaft 67, to mesh with pinion 69; the pinion 71 mounted on shaft 115 67, and arranged to rotate with gear wheel 70, and gear wheel 72, which is keyed on shaft 68, as by key 73, Fig. 3, to rotate therewith. The teeth on said wheel 72 are arranged to mesh with the teeth on pinion 71. 120

By the above means, when the clutch members 62, 64, are engaged in the manner hereinbefore described, by the movement of handle 59, (to the right as viewed in Fig. 2), the shaft 68 is rotated by the rotation of 125 shaft 54; but at a greatly reduced speed.

74 represents an eccentric which is rigidly mounted on shaft 68, to turn therewith. 75 represents an eccentric strap made of two parts and mounted on eccentric 74; 130

said parts or members being secured together by bolts 76. The strap 75 is provided with depending member 77, having a recess at the lower end thereof in which the joined upper ends of members 35 and 36 of the additional toggle joint extend, and with an aperture in which pin 43 extends.

When the shaft 52 is turned to adjust members 48, it is manually operated, preferably by a Stillson wrench.

The operation of the machine is; the motor X being energized and the members 62 and 64 of the friction clutch being engaged, shafts 54, 67 and 68 are rotated. Thereby eccentric 74 is turned and depending member 77 of eccentric strap 75 is forced down and the additional toggle joint formed by members 35 and 36 is actuated and said members are forced into a substantially horizontal plane. The bars 34 are thereby forced longitudinally, one to the left and one to the right as viewed in Fig. 1, and the two series of toggle joints formed by the members 25 are forced into substantially vertical planes, thereby forcing bar 24 and upper die 23 down, and on to a sheet or strip of metal interposed between dies 18 and 23.

The clutch members 62 and 64 being held in engagement until the shaft 68 has made a complete revolution, or substantially so, the several toggle joints will be returned to the position illustrated in Figs. 1 and 2, with die 23 raised from die 18.

In placing a strip or sheet of ductile metal between dies 18 and 23, of less length or width than the length of said dies, the ends or sides of said strip or sheet is placed at substantially equal distances from the ends of the dies.

I claim:

1. In a bending machine, two series of toggle joints, pivots joining the meeting ends of the members of said joints, one of said series comprising a plurality of toggle joints, the pivotally joined ends of said members being normally on one side of vertical planes parallel to the ends of the machine and extending through the additional pivots of said members, and the other of said series comprising a plurality of toggle joints the pivotally joined ends of said members being normally on the other side of vertical planes also parallel to the ends of the machine and extending through the additional pivots of said last named members, bars horizontally mounted on said pivots to connect the pivotally joined ends of the members of each series, in combination with an additional toggle joint, one end of the members thereof pivotally joined and the other end of said members pivotally connected to said horizontal bars adjacent to the ends thereof, means to force said joined ends to move the members of said

additional toggle joint substantially into a horizontal plane and the members of the toggle joints of both said series into substantially vertical planes, a bar mounted on the lower ends of the lower members of said series of toggle joints, a die on said bar, and an additional die, said dies arranged to co-act.

2. In a bending machine, two series of toggle joints, pivots joining the meeting ends of the members of said joints, one of said series comprising members the pivotally joined ends whereof are normally on one side of vertical planes parallel to the ends of the machine and extending through the additional pivots of said members, and the other of said series comprising members the pivotally joined ends whereof are normally on the other side of vertical planes also parallel to the ends of the machine and extending through the additional pivots of said last named members, means to vertically adjust the upper ends of the upper members of said series, bars horizontally mounted on said first named pivots to connect the pivotally joined ends of the members of each series, in combination with an additional toggle joint, one end of the members thereof pivotally joined and the other end of said members, respectively, pivotally connected to one of said horizontal bars, means to force said joined ends to move the members of said additional toggle joint substantially into a horizontal plane and the members of the toggle joints of both said series into substantially vertical planes, a bar, pivots arranged to attach said bar to the lower ends of the lower members of said series of toggle joints, a die on said bar and an additional die, said dies arranged to co-act.

3. In a bending machine, two series of toggle joints, pivots joining the meeting ends of the members of said joints, one of said series comprising members whereof said meeting ends are on one side of vertical planes parallel to the ends of the machine and extending through the additional pivots of said members, and the other of said series comprising members whereof the meeting ends are on the other side of vertical planes also parallel to the ends of the machine and extending through the additional pivots of said last named members, when said toggle joints are in normal position, bars horizontally mounted on said pivots to connect the pivotally joined ends of the members of each series, an additional toggle joint, one of the ends of the members thereof pivotally joined, and the other of the ends of said members pivotally connected to said horizontally mounted bars, in combination with a rotatably mounted shaft, an eccentric rigidly mounted on said shaft, controlled means to turn said shaft, an eccentric strap,

a depending member on said strap, the lower end of said depending member connected to the pivot joining the meeting ends of said additional toggle joint, a bar, pivots arranged to attach said bar to the lower ends of the lower members of said series of toggle joints, a die on said bar and an additional die, said dies arranged to co-act.

4. In a bending machine, two series of 10 toggle joints, pivots arranged to join the meeting ends of the members of said joints, said pivots in one of said series normally positioned to one side of vertical planes parallel to the ends of the machine and extending through the additional pivots of 15 said members, and said pivots in the other one of said series normally positioned on the other side of vertical planes also parallel to the ends of the machine and extending 20 through the additional pivots of said last named members, bars horizontally mounted on said pivots to connect the pivotally joined ends of the members of each series, means to vertically adjust the upper ends 25 of the upper members of said series, an additional toggle joint, one of the ends of the members thereof pivotally joined and the other of the ends of said members pivotally connected to said horizontally mounted bars, 30 in combination with a rotative shaft, controlled means to turn said shaft, an eccentric rigidly mounted on said shaft, an eccentric strap, a depending member on said strap, the lower end of said depending member 35 connected to the pivot joining the meeting ends of the members of said additional toggle joint, a bar, pivots arranged to attach said bar to the lower ends of the lower members of said series of toggle joints, a die 40 on said bar, and an additional die, said dies arranged to co-act.

5. In a bending machine, two series of 45 toggle joints, pivots arranged to join the meeting ends of the members of said joints, said pivots in one of said series normally positioned on one side of vertical planes parallel to the ends of the machine and extending through the additional pivots of 50 said members, and said pivots in the other one of said series normally positioned on the other side of vertical planes, also parallel to the ends of the machine and extending through the additional pivots of said last-named members, bars horizontally mounted 55 on said pivots to connect the pivotally joined ends of said members of each series, members arranged to be vertically movable, additional pivots arranged to connect the lower ends of said vertically movable members to 60 the upper ends of the upper members of said series of toggle joints, means to adjustably control the position of said vertically movable members, in combination with an additional toggle joint, one of the ends of the 65 members thereof pivotally joined and the

other one of said ends pivotally connected to said horizontally mounted bars, means to move the joined ends of said members of said additional toggle joint so that said members are substantially in a horizontal plane and 70 the members of said series of toggle joints are substantially in vertical planes, a bar, pivots arranged to connect said bar to the lower ends of the lower members of said series of toggle joints, a die on said bar and 75 an additional die, said dies arranged to co-act.

6. In a bending machine, a plurality of 80 vertical metal plates secured in parallel planes, portions of the sides of said plates removed to obtain a plurality of horizontal supports and a like number of over-hanging portions of said plates above said tables, in combination with a bar adapted to form 85 the base of a die, a die on said base, an additional bar, an additional die on said additional bar arranged to co-act with said first named die, controlled means to move said additional bar, said means to move comprising a plurality of series of toggle joints 90 positioned below said over-hanging portions of said vertical plates, and means to actuate said toggle joints.

7. In a bending machine, a plurality of 95 metal plates secured vertically in parallel planes and having portions removed from one of the sides thereof to obtain horizontal supports and over-hanging portions above said supports, in combination with a die base mounted on said supports, a die on said 100 base, a bar movably mounted below said over-hanging portions and an additional die attached to said bar, said additional die arranged to co-act with said first named die, a plurality of vertical members adjustably 105 mounted on said overhanging portions, means connecting said vertical members to uniformly adjust the same, a plurality of toggle joints pivotally connected to said movably mounted bar and to said adjustably 110 mounted vertical members, and controlled means to jointly actuate said toggle joints.

8. In a bending machine, a plurality of 115 metal plates secured vertically in parallel planes and having a portion removed from one of the sides of each thereof to obtain horizontal supports and over-hanging portions above said supports, in combination with a die base mounted on said supports, a die on said base, a bar movably mounted 120 below said over-hanging portions and an additional die attached to said movable bar, said additional bar arranged to co-act with said first named die, a plurality of vertical members adjustably mounted on said overhanging portions, means connecting said vertical members to uniformly adjust the same, a plurality of toggle joints pivotally connected to said movably mounted bar and to said adjustably 125 mounted vertical mem- 130

bers, an additional toggle joint, a plurality of horizontal bars arranged to connect the joined ends of the members of said plurality of toggle joints, pivots, the members of said additional toggle joint pivotally connected by one of said pivots and said members of said additional toggle joint connected to said

horizontal connecting bars by additional ones of said pivots, and controlled means to move the members of said additional toggle joint from their normal position substantially into a horizontal plane. 10

THOMAS J. KELLEHER.
